UNITED STATES PATENT OFFICE.

IRVING F. NILES, OF PLAINFIELD, NEW JERSEY, ASSIGNOR TO R. HOE AND CO., OF NEW YORK, N. Y., A CORPORATION OF NEW YORK.

PRINTING-MACHINE.

1,155,505.

Specification of Letters Patent.

Patented Oct. 5, 1915.

Application filed January 3, 1913. Serial No. 739,993.

To all whom it may concern:

Be it known that I, IRVING F. NILES, a citizen of the United States, residing at Plainfield, county of Union, and State of New Jersey, have invented certain new and useful Improvements in Printing-Machines, fully described and represented in the following specification and the accompanying drawings, forming a part of the same.

10 This invention relates to improvements in printing machines.

Transfer printing machines as now ordinarily constructed employ three cylinders, said cylinders being arranged to make turn 15 for turn with each other. Where it is desired to use a flat sheet delivery with such cylinders, a traveling sheet carrier, such, for instance, as chains provided with grippers, is located beneath the impression cylinder.

20 In the operation of this mechanism, the sheet is first taken by grippers from a feed-board or other similar source, carried around and printed, after which the grippers release the head of the sheet which is transferred to the grippers on the traveling carrier. In such machines it is desirable to deliver the sheet printed side up. This requires that the chains or sheet carrier travel in a direction opposite to the direction of 25 travel of the impression cylinder, so that the direction of travel of the sheet has to be changed as soon as it is taken by the grippers on the chains. When, however, material, such as cardboard, is being 30 printed, considerable difficulty is experienced in thus changing the direction of the sheet, and there is, furthermore, liability of tearing a sheet and injuring the design when the direction of travel is changed in 35 the manner referred to. Further, a carrier having sheet seizing devices such as grippers, is practically necessary in these constructions, as the head of the sheet must be positively taken, and such carriers are cumbersome and expensive in construction.

40 The object of the present invention is to produce an improved printing machine in which the sheets may be delivered flat and with the printed side up, and to accomplish 45 this without changing the direction of travel of the sheet.

With this and other objects in view, the invention consists in certain constructions,

and in certain parts, improvements and combinations as will be hereinafter specifically described and pointed out.

Referring to the accompanying drawings:—Figure 1 is a diagrammatic side elevation of so much of a printing machine as is necessary to an understanding of the invention. Fig. 2 is a diagrammatic view similar to Fig. 1, but with certain parts removed, the position of the cylinders being that which they occupy at about the time the printing is begun. Fig. 3 is a view similar to Fig. 2 but showing the sheet at about the time the delivery from the impression cylinder to the sheet receiving surface of its coöperating cylinder is effected.

Referring to the drawings which illustrate a concrete embodiment of the invention, 1 indicates a printing cylinder having a printing surface 2 and a non-impression sheet receiving surface 3, serving merely to hold and carry a sheet without functioning in the making of an impression on said sheet. Suitable sheet holding devices, as grippers 4, are provided which coöperate with the sheet receiving surface. In machines embodying the invention in its best form, the printing surface 2 will be a planographic surface, such, for instance, as the rubber blanket ordinarily employed on transfer cylinders, this blanket being secured on the cylinder in any of the well-known ways.

When the invention is embodied in a transfer printing machine, a design carrying cylinder, such as 5, will be provided, this cylinder receiving the ink from a battery of the usual character, generally indicated at 6. In the best constructions embodying the invention, this design carrying cylinder will be arranged to make two revolutions to each revolution of the cylinder 1, thus causing the design to pass the inking rolls twice, so that the ink may be thoroughly worked into the design.

Suitable coöperating impression means will, of course, be provided. In the particular construction illustrated, this impression means consists of a cylinder, as 7, this cylinder being arranged to make two revolutions to one of the cylinder 1. On what may be termed the first revolution, the cylinder 7 coöperates with a printing surface 2 and

2

effects the printing, and on the second revolution, it coöperates with the sheet receiving surface 3 and delivers the sheet thereto. This cylinder 7 will be provided with any suitable sheet taking devices, such, for instance, as grippers 8. Sheets may be delivered to the cylinder 7 in any suitable way. In the particular construction illustrated there is provided a feedboard 9. The usual 10 front stops, indicated at 10, are provided, these front stops being raised and lowered from a cam on the shaft 11 of the cylinder 7, this cam coöperating with the usual forked actuating rod 12. The feed-board will ordinarily be raised in order to permit the sheet to pass its guide fingers on the second revolution of the cylinder 7. In order to effect this, the feedboard is hinged or pivoted, as indicated at 12', and is raised or lowered 15 from a rock-shaft 13, this rock shaft being operated from a cam 14 on the shaft 15 of the cylinder 1, the construction being a usual one.

The flat delivery mechanism employed 20 may be of any suitable type. As shown, it consists simply of tapes 16 running over the ordinary tape rolls 17. If desired, a stripper of usual form, indicated at 18, may be employed to effect the clearing of the sheet 25 from the sheet receiving surface 3.

In the construction described, the sheets are fed from the feedboard 9 to the grippers on the cylinder 7, and as this cylinder makes its first revolution, the sheets are printed, the 30 position of the parts being shown in Fig. 2. As the cylinder makes its next revolution, the sheets are delivered from the grippers 8 to the grippers 4 on the cylinder 1 and are laid against the sheet receiving surface, the 35 printed side of the sheets being toward the surface. As this cylinder 1 continues its revolution, the grippers 4 are opened and the sheets deposited printed side up on the tapes 16. It will be seen that by the construction 40 described the sheets are carried directly through the machine and delivered printed side up without any change in their direction of movement.

Changes and variations may be made 45 in the construction by which the claimed invention is carried into effect, and it will be understood that while the invention is of particular value in transfer machines, it may be embodied, as to some of its features, 50 in machines which do not employ transfer or printing surfaces.

What is claimed is:—

1. In a printing machine, the combination with a cylinder having a printing surface, and a non-impression sheet receiving surface, of an impression cylinder making two revolutions to one of the cylinder having the printing surface, said cylinder coöperating with the printing surface on one revolution and delivering the sheet to the non-impression sheet receiving surface on the next revolution, and a flat delivery mechanism coöperating with said sheet receiving surface. 60

2. In a transfer printing machine, the combination with a cylinder having a planographic printing surface and a non-impression sheet receiving surface, of a design carrying cylinder for delivering the design to the printing surface, a flat delivery coöperating with the sheet receiving surface to 70 which the sheets are delivered printed side up from the sheet-receiving surface, and co-operating impression means. 75

3. In a transfer printing machine, the combination with a cylinder having a planographic printing surface and a non-impression sheet receiving surface, of a design carrying cylinder for delivering the design to the printing surface, a flat delivery coöperating with the sheet receiving surface, and 80 an impression cylinder making two revolutions to one revolution of the cylinder having the printing surface, said cylinder coöperating with the printing surface to print the sheet on one revolution and delivering 85 the sheet to the sheet receiving surface on the next revolution. 90

4. In a transfer printing machine, the combination with a cylinder having a planographic printing surface and a non-impression sheet receiving surface, of a design carrying cylinder for delivering the design to the printing surface, said cylinder being arranged to make two revolutions to each of the cylinder having the design carrying surface, an impression cylinder making two revolutions to one of the cylinder having the printing surface, and a flat delivery mechanism coöperating with the sheet receiving surface. 100

In testimony whereof, I have hereunto set my hand, in the presence of two subscribing witnesses.

IRVING F. NILES.
